UNITED STATES PATENT OFFICE.

FRANK J. FRUNZ AND JOHN W. FRUNZ, OF PATTERSON, CALIFORNIA.

AUTOMATIC AIR VALVE.

Application filed July 22, 1924. Serial No. 727,590.

To all whom it may concern:

Be it known that we, FRANK J. FRUNZ and JOHN W. FRUNZ, citizens of the United States, residing at Patterson, in the county 5 of Stanislaus and State of California, have invented certain new and useful Improvements in Automatic Air Valves, of which the following is a specification.

This invention relates to an improved 10 automatic air valve for use in conjunction with internal combustion engines, preferably of the type used by automobiles.

It is our object to provide a valve which 15 is automatically controlled according to the speed of travel of the vehicle, so that when the vehicle is running slowly, a comparatively small amount of air will be admitted, whereas when the speed is increased, the 20 valve will be opened to a greater degree to admit more air.

One feature of the invention is the provision of the structure for accomplishing this end which is such as to permit the same 25 to be installed to cooperate with existing or stock parts without requiring extensive alterations of the latter.

More specifically speaking, we propose to 30 operate the device from some driven part of the vehicle, for instance, from the speedometer operating gear or one of the front wheels and to include in the structure an automatically controlled governor, which acts directly on the air valve, for opening 35 and closing the same.

Other features and advantages will become 40 apparent during the following description and drawing:

In the accompanying drawing, forming a 45 part of this application, and in which like numerals are employed to designate like parts throughout the same:

Figure 1 is a central vertical section with 50 parts in elevation, of a device constructed in accordance with the present invention, showing the position of parts when the device is not in operation.

Figure 2 is a transverse section, taken substantially on the plane of the line 2—2 of Figure 1.

Referring to the drawings, the reference 55 character 1 indicates an air intake for an internal combustion engine, which is constructed as seen more clearly in Figure 2, to form a guide 2 for a sliding valve 3. A governor indicated as at 4 as a whole, acts on the valve through the medium of the ring

like member 5, which has oppositely extending arms 6 connected to extensions 7, on the valve. The ring like part 5 surrounds the sliding sleeve 8 of the governor, this sleeve 60 being in turn slidable upon the shaft 9 has a stop collar 10 to limit the sliding movement of the sleeve, in one direction. The shaft 11 of the governor has a reduced portion forming a journal 12, and this journal carries a 65 pinion 13, with which a gear 14 meshes for imparting rotation to the shaft 11. The governor is enclosed within the casing 15, which is formulated at its top to provide a bearing for the journal 12. The casing carries a bracket 16, which in turn carries a bearing 17, for the flexible driving shaft 18. The casing 15 is shaped to permit free action 70 of the weighted arm of the governor and it has its bottom shaped to provide attaching 75 flanges 19, by means of which it is connected to the intake 1. Furthermore, the aforesaid valve 3 is provided with a central pocket 20, for reception of the lower end of the shaft 9.

From the foregoing description, it is obvious 80 that when the shaft 18 is set in rotation, the gearing will rotate the governor. As is usual, the centrifugal force will slide the sleeve 8 up on the shaft 9, as the speed of rotation increases, and the valve 3 will be 85 lifted through the medium of the connections 5 and 6. Thus, the greater the speed of the vehicle the greater the amount of air supplied to the engine, and vice versa. By properly proportioning the supply of air 90 with respect to the speed of travel of the vehicle, smooth running is insured, and a more effectively operating engine is assured. Normally, the sliding valve is slightly open, so as not to interfere with the starting of an 95 engine with which it is used.

A careful consideration of the description in connection with the drawing will enable persons skilled in the art to which the invention relates to obtain a clear understanding 100 of the same. Therefore, a more lengthy description is deemed unnecessary.

Although we have shown and described the preferred embodiment of our invention, it is to be understood that minor changes 105 coming within the scope of the adjoined claim may be resorted to, if desired.

We claim:

A device of the class described comprising 110 an intake pipe, a valve arranged transversely in said pipe and adapted for vertical sliding movement, a casing mounted upon said pipe,

said casing being provided with a bearing, a centrifugal governor arranged in said casing, the shaft of said governor being journaled for rotation in said bearing, a pinion carried by said shaft, said valve being provided with a central pocket open at its top, the lower end of said shaft telescoping into said pocket and being provided with spaced shoulders, said governor including a

sleeve slidable upon the shaft between said shoulders, and a yoke having its arms connected to said valve and provided with a central ring through which said governor sleeve passes.

In testimony whereof we affix our signatures.

FRANK J. FRUNZ.
JOHN W. FRUNZ.
